Primary Examiner — Karen E Kearney

(74) Attorney, Agent, or Firm — Banner & Witcoff, Ltd.

(57) **CLAIM**

The ornamental design for a display screen with graphical user interface, as shown and described.

DESCRIPTION

The FIGURE is a front view of a display screen with graphical user interface showing our new design.

The broken line showings of the two circles, a portion of the graphical user interface, and portions of the display screen form no part of the claimed design.
